UNITED STATES PATENT OFFICE

FRANK SMITH, OF CINCINNATI, OHIO

DESIGN FOR A HANGER HOOK

Application filed December 20, 1929. Serial No. 33,868. Term of patent 7 years.

To all whom it may concern:

Be it known that I, FRANK SMITH, a citizen of Canada, and a resident of Cincinnati, in the county of Hamilton and State of Ohio, have invented a new, original and ornamental Design for a Hanger Hook, of which the following is a specification, reference being made to the accompanying drawing, forming part thereof.

Fig. 1 is a front elevational view of a hanger-hook showing my new design.

Fig. 2 is a side elevational view of the same.

I claim:

The ornamental design for a hanger-hook as shown.

FRANK SMITH.
